UNITED STATES PATENT OFFICE

JOHN E. MARSDEN, OF PHILADELPHIA, PENNSYLVANIA

DESIGN FOR A TUMBLER OR SIMILAR ARTICLE

Application filed May 2, 1929. Serial No. 31,074. Term of patent 7 years.

To all whom it may concern:

Be it known that I, JOHN E. MARSDEN, a citizen of the United States, residing in Philadelphia, in the county of Philadelphia and State of Pennsylvania, have invented a new, original, and ornamental Design for Tumbler or Similar Article, of which the following is a specification, reference being had to the accompanying drawing, forming a part thereof, and which shows in—

Fig. 1 a view in vertical elevation of a tumbler showing my new design, and in Fig. 2 a plan view thereof.

The tumbler includes a plurality of annular rings constituting less than one half the length of the tumbler, above which rings is a curved portion about one half of the said length, the diameters at the ends of the curved portion being substantially equal, and a flaring rim portion.

I claim:

The ornamental design for a tumbler or similar article as shown and described.

JOHN E. MARSDEN.
